ELIMINATOR SCREEN FOR EVAPORATIVE TOWERS AND THE LIKE

Madan L. Ghai, Manchester, and Joseph A. Koren, Hartford, Conn., assignors, by mesne assignments, to Dunham-Bush, Inc., West Hartford, Conn., a corporation of Connecticut

Application September 1, 1955, Serial No. 532,054

8 Claims. (Cl. 183—75)

This invention relates to the removal of suspended water particles from an air stream, and more in particular to the eliminator screen in apparatus, such as cooling towers where water is evaporated in a fast moving stream of air.

An object of this invention is to remove water particles from an air stream. A further object is to remove particles from an air stream or the like with minimum static pressure drop and in an efficient, dependable manner. A further object is to improve the operation of cooling towers and the like by providing for the removal of water particles from the air stream in an improved manner. A further object is to provide improved structures and methods for removing water particles from the air in such a way as to avoid the difficulties which have been encountered in the past. A still further object is to provide for the above with structure which is simple and sturdy, inexpensive to manufacture and install, readily serviced, and dependable and efficient in use. These and other objects will be in part obvious and in part pointed out below.

In the drawings:

Figure 1 is a side elevation of a cooling tower incorporating one embodiment of the invention, with parts broken away;

Figure 2 is a somewhat enlarged view on the line 2—2 of Figure 1;

Figure 3 is an enlarged fragmentary view showing the details of the structure of Figures 2, 4 and 5, and the mode of operation;

Figure 4 is an enlarged sectional view on the line 4—4 of Figure 3; and,

Figure 5 is a sectional view on the line 5—5 of Figure 3.

In refrigeration systems of a size greater than the order of three tons capacity, it has been increasingly common practice to provide evaporative cooling towers. With such apparatus, water is sprayed into a fast moving stream of air to evaporate water and dissipate heat. The water may be circulated from the tower to the condenser of the refrigeration system or the condenser of the refrigeration system may be located in the tower. Such towers are frequently positioned upon a roof or elsewhere high above the ground. Frequently, such towers have been considered objectionable because of the noise which they produce and also because of the tendency for such towers to expel water particles in the air stream which passes from them. The most serious object to such towers often comes from people who pass near the tower within range of the escaping water particles. In the past, attempts have been made to remove all the particles from the air stream, but this has involved the provision of the air-escape louvers which passed the air in thin streams along zig-zag paths. Such arrangements are apt to increase materially the static pressure drop in the air stream so that

2

the air circulation is reduced unless fan equipment was enlarged. However, the enlargement of the fan equipment tends to increase the power requirements and the cost of operation; and, it also increases the noise produced by the unit. It is among the objects of the present invention to overcome these problems and to avoid the difficulties which have been encountered with this type of apparatus in the past. This is accomplished by providing an improved eliminator screen structure for removing water particles from the air stream passing from the cooling tower.

Referring particularly to Figure 1 of the drawings, an evaporative cooling unit 2 has a finned condenser coil 4 positioned within a casing 6 and cooled by simultaneously passing water and a stream of air through it. The stream of air is drawn in at the right at 8, passes horizontally and somewhat upwardly through the coil 4, and is discharged at the left through an air discharge opening 10 by a fan 12 driven by a motor 14. Water is supplied to coil 4 from a distributor pan 16 which is rectangular and has bottom openings from which small streams of water pass. The water is intercepted and dispersed by a water distributor screen 18 and covers the entire face of coil 4. The water flows through coil 4 downwardly and the right; and, some of the water is evaporated, and the remainder is collected in a bottom sump and is recirculated by a pump not shown.

The air passing from the condenser coil 4 has been and has become saturated with moisture, and it also contains considerable water in the form of small particles. The present invention is concerned primarily with the removal of these small particles of water from the air. Accordingly, an eliminator screen 20 is positioned between the condenser coil 4 and fan 12, and all of the air passing to the fan flows through this eliminator screen. This eliminator screen is constructed as shown best in Figure 2, and has a rectangular wooden frame 22 with side upright members, top and bottom members 26, and a central upright member 28. Stapled to the two side faces of frame 22 are two identical screens 30 and 32 which are formed of thin sheet metal which has been fabricated in a manner discussed below to provide water eliminating louvers.

The louver construction constitutes vertical rows 34 of louvers 38 having slots 39 therebetween, and between the rows 34 are vertical imperforate strips 36. The louver construction is shown best in Figures 3, 4, and 5, where a portion of a row 34 is shown, together with the adjacent imperforate strips 36. In this connection, the screen is considered from the face shown in Figure 5, which is positioned toward the oncoming stream of air during operation. The individual louvers 38 are flat strips of the sheet metal integral at their ends with the imperforate strips 36. The louvers extend longitudinally at an angle of 45° to the horizontal, and they also are twisted from the original plane of the sheet metal to substantially a 45° angle. That is, the bottom edge 40 is moved outwardly, while the top edge 42 is moved inwardly (see Figure 5), but the louver maintains its original flat condition.

Also, the left-hand end of each louver (that is, the lower end) is positioned outwardly so that it extends somewhat above the original plane of the sheet metal, whereas at the opposite (i. e., upper right-hand) end the louver is somewhat depressed. Hence, each louver extends from the top from somewhat below the original plane of the sheet metal downwardly and to the left, and through this plane. Each of the imperforate strips 36 between the two rows of louvers is provided with a vertical channel or trough 46 which (see Figure 4) is somewhat an open-V in cross section, and this is below

the level of the original plane of the sheet metal. As indicated above, there are two identical screens 30 and 32, and the relationship between these two screens is shown best in Figure 4. That is, each of the screens 30 and 32 has its face with the troughs 46 thereon facing the air stream, and the streams are spaced a substantial distance apart.

The louver-forming operation involves cutting parallel slits into the sheet metal along the side edges of the louvers being formed, and the forming tools simultaneously push the lower edge of each louver outwardly, and the upper edge of each louver inwardly. The operation also includes the forming of the troughs 46. Illustratively, these eliminator screens are fabricated from strips of brass .008 inch thick and substantially 8 inches wide. After the louver construction has been formed, the individual strips are stapled together at their edges to form the entire assembled screen.

In this embodiment, the channels are spaced $15\frac{1}{16}$ of an inch apart, center to center, and the width of the strip forming each of the vertical channels is substantially $\frac{3}{16}$ inch. Hence, the width of each row of louvers is $\frac{3}{4}$ inch. Hence, each of the louvers is of a length of substantially one inch.

During operation, the stream of air approaches the eliminator screen from the bottom of Figure 4 toward the face of screen 30, shown in Figure 3. The louvers tend to divert the air somewhat upwardly through the slots 39, and these slots are of sufficient size to permit satisfactory flow of the air. However, particles of water entrained in the air stream are impacted against the louvers and they cling to the louvers. The initial water particles impinging on the louver surfaces tend to wet these surfaces, but as additional water is deposited, it accumulates and starts to flow downwardly along the louvers. This flow is represented in Figure 3, and at the lower end of each louver the water flows into the adjacent trough 46. Hence, each trough collects water from the adjacent row of louvers and within this trough the water is no longer subjected to the entraining forces of the air stream, so that it flows downwardly along the trough to the bottom of the eliminator screen. Here the water flows from the eliminator screen to the sump tank. As shown best in Figure 1, the eliminator screen 20 is at a small angle to the vertical, so that it inclines upwardly against the air stream. This positioning of the screen and the form and position of the louvers insure that the net effect of the actions of gravity and the air stream is for the water to flow down the louvers into the troughs, and thence down the troughs.

Referring again to Figure 4, the discussion immediately above concerns the eliminator action at screen 30. After the air passes through screen 30, it passes on and approaches the face of screen 32. Here the water eliminating action is repeated, with the air being diverted somewhat upwardly and with any remaining particles of water impinging upon and being deposited upon the louvers of screen 32. Under some circumstances, it may be desirable to provide additional screens, but it has been found that two screens are very adequate for the particular embodiment here being discussed.

The suspended water particles are separated from the air stream with the structure herein disclosed, with minimum static pressure drop, and the water removed is not re-entrained into the air stream. The louvers present sufficient impingement area to collect the water, and the free openings between them permit the air to pass. The inclination of the louvers lengthwise, with the appropriately spaced channels or troughs, insure the removing of the moisture which is collected.

Under some circumstances, the faces, relative proportions and positionings of the louver may be varied, while not losing certain or all of the advantages of the inven-

tion. The open-V trough or channel provides a water stream which flows downward without being disturbed by the air stream. Under some circumstances the form of the trough may be varied and a single trough may be provided for two rows of louvers. Also the louvers may be slanted downwardly so that they tend to deflect the air in a downward direction instead of upwardly in which case the louvers may be more nearly vertical to insure that the water will flow down them by surface flow. Under some circumstances the louvers of screen 30 may be slanted as herein shown, whereas the louvers in screen 32 may be slanted oppositely, either downwardly or upwardly and to the right (in Figure 4).

As many possible embodiments may be made in the above invention and as many changes might be made in the embodiment above set forth, it is to be understood that all matter hereinbefore set forth or shown in the accompanying drawings is to be interpreted as illustrative and not in a limiting sense.

We claim:

1. An apparatus of the character described, an eliminator screen comprising, a frame construction, and an eliminator screen supported by said frame construction formed by sheet metal and comprising a plurality of vertically extending rows of louvers having passageways therebetween and trough means adjacent each of said rows, said louvers being positioned at an angle to the horizontal and extending downwardly toward said trough means whereby liquid collecting on said louvers flows downwardly therealong to said trough means and thence in a protected stream downwardly toward the bottom of said screen.

2. Apparatus as described in claim 1, wherein each of said louvers is turned about its axis to an angle of substantially 45° from the general plane of the screen and extends longitudinally at an angle of substantially 45° from the horizontal.

3. Apparatus as described in claim 1, wherein each of said louvers has its lower end extending outwardly from the general plane of the screen whereby the liquid passes by surface flow to said trough means.

4. Apparatus as described in claim 3, wherein said trough means is in the form of an open-V trough.

45 5. Apparatus as described in claim 4, wherein said louvers are of the order of one inch in width and said trough means is formed in a strip of imperforate sheet metal having a width of the order of $\frac{3}{16}$ inch.

60 6. An eliminator screen construction which is adapted to remove liquid particles from a fast-flowing air stream comprising, a sheet metal screen formed of parallel vertical rows of louvers with a vertical channel positioned between each row and the next, said louvers being positioned at an angle of the order of 45° from the horizontal and with the planes slanting generally upwardly at an angle from the horizontal whereby each louver presents an impacting surface to intercept liquid particles and liquid accumulating thereon flows downwardly to the adjacent vertical channel.

65 7. Apparatus as described in claim 6, which includes a second screen parallel to the first-named sheet metal screen and similar thereto.

8. Apparatus as described in claim 7, which includes a wooden frame providing support for said sheet metal screen.
